UNITED STATES PATENT OFFICE.

WILLIAM H. TRAYER AND FRANK CAMPBELL, OF CARLISLE, PENNSYLVANIA.

MUSIC-BOOK HOLDER AND LEAF-TURNER.

1,005,673.

Specification of Letters Patent. Patented Oct. 10, 1911.

Application filed May 20, 1910. Serial No. 562,474.

To all whom it may concern:

Be it known that we, WILLIAM H. TRAYER and FRANK CAMPBELL, citizens of the United States, residing at Carlisle, in the 5 county of Cumberland and State of Pennsylvania, have invented new and useful Improvements in Music-Book Holders and Leaf-Turners, of which the following is a specification.

10 This invention relates to music book holders and leaf turners of that type in which a leaf can be turned over and back again as required, the musician having merely to press upon a button to effect the turning of 15 the leaf.

The invention has for one of its objects to provide an extremely simple, inexpensive and practical device of this character which 20 stably supports the music book in open position while the second leaf of the music can be freely turned and re-turned without requiring the performer to stop playing.

Another object of the invention is the provision of a novel form of music leaf turning element which consists of members engaging the leaf to be turned at its opposite sides adjacent the binding, said members having laterally projecting transparent arms which extend horizontally across opposite faces of the sheet or leaf at a point intermediate its top and bottom so that as 30 the element turns, the leaf or sheet will turn with it.

Another object of the invention is the provision of a novel arrangement of up-standing members on a supporting base or rest which serve to hold the music book open.

With these objects in view and others as 40 will appear as the description proceeds the invention comprises the various novel features of construction and arrangement of parts which will be more fully described hereinafter and set forth with particularity 45 in the claim appended hereto.

In the accompanying drawing, which illustrates one embodiment of the invention:—Figure 1 is a perspective view of the apparatus. Fig. 2 is a plan view thereof 50 showing a music book in position, and one leaf thereof at an intermediate position in its turning. Fig. 3 is a longitudinal section of the device showing by dotted lines the book-holding members folded. Fig. 4 55 is a central transverse section. Fig. 5 is a detail view of the operating means for the

leaf turning element. Fig. 6 is an enlarged perspective view of a leaf turning element with portions broken away.

Similar reference characters are employed to designate corresponding parts throughout the several views.

Referring to the drawing, A designates the base of the apparatus which may be a strip of wood to form a support or rest for 60 the music book, the under surface of the base being provided with transverse strips 1 of felt so that when the apparatus is placed on a music holder of a piano or organ, it will not scratch or mar the instrument, and also on the base may be provided spring clips 2, whereby the apparatus can be fastened to a music rack. At the center of the base A is a chamber 3 extending from the top to the bottom in which is 65 mounted a frame B that supports the operating means for the leaf-turning element. This means comprises a central vertical shaft 70 4, which is provided with a pinion or gear 5 that meshes with oppositely disposed rack 80 bars 6 and 7 that slide horizontally in guides 8 on the frame B, and projecting forwardly from the rack bars are stems or rods 9 that pass forwardly through openings 10 in the base and on these rods are push buttons 12 arranged side by side. When one push button is in the other is out and while the outer one is pushed inwardly, the other moves outwardly. The shaft 4 projects out 75 of the frame B and has its upper end so 85 constructed as to detachably connect with the leaf turning element C. The frame B is held in the chamber of the base by clips 13 secured to the base and projecting under the frame. On the front edge of the base 90 is a metal piece 14 through which the push-button stems extend, and upon removal of this plate and the clips 13, the frame B can be taken out.

The leaf-turning element C consists of 100 two upwardly extending rods 15 which have their lower ends anchored in a base 16 that is in the form of a ring which fits over the projecting end of the shaft 4 and extending 105 diametrically of the ring and secured thereto is a key 17 which fits in a slot 18 in the upper end of the shaft 4. It is merely necessary to slip the base member of the leaf-turning element over the shaft to lock the element thereon, and the removal of the 110 element is correspondingly easy. The upper ends of the rods 15 are bent horizontally

to afford connection with transparent arms 19. These arms may be in the form of celluloid or other transparent strips and they are adapted to engage the body portion of 5 the leaf to be turned, and since they are transparent, they will not conceal any of the notes of the music. The leaf to be turned is inserted between the rods or bars 15 which can be sprung apart in adjusting 10 the leaves thereto and the book will be so supported that these rods will be parallel with the binding of the book and as close as possible thereto. Hence, as the element turns on its own axis, it will cause the leaf 15 to turn through 180°. For each apparatus, the leaf-turning elements of different heights will be employed for different size music, it being preferable to have the arms 19 engage the leaf near the middle thereof.

20 In order to support the book in upright position, a plurality of upstanding members or supports are provided on the base A. The covers of the book are adapted to rest against and extend in front of the upwardly extending members 20 disposed a suitable distance apart at opposite sides of the center of the base and in a line behind the leaf-turning element. The lower ends of 25 these members are disposed in sockets 21 in the base and are mounted on horizontal pivots 22 so that these members can fold inwardly toward the center in over-lapping relation so as to take up less room and permit the device to be folded for transportation.

30 The covers and leaves of the books that are not to be turned are held back by means of short upwardly extending members 23 which are pivoted in a socket 24' in the base so as to fold flat against the latter.

35 These members are short so as not to conceal any of the music as they engage the first and fourth pages of the music that is being played. These members 23 are set inwardly near the leaf-turning element, and 40 also forwardly of the rear supporting members 20. The central portion or back of the book is mounted on a central support or rest D which is disposed immediately behind the leaf turning element. This support 45 is constructed of a single piece of wire that has its end bent into short upstanding members 24 that engage behind the book and coöperate with the members 20 and 23

to hold the book rigidly in place. The members 24 have horizontal base portions 55 25 that are connected with a bar portion 26, there being eyes 27 at the ends of the bar for receiving screws 28 that fasten the device D to the base. The intermediate portion of the bar 26 is formed into a forwardly extending central tongue 29 which terminates adjacent the base of the leaf-turning element, and the bottom edge of the back of the book rests on this tongue. It will thus be obvious from Fig. 2, that 60 65 two bars or back supports are provided for the book, namely, the members 20 and 24 and single front supports 23. In order to prevent the leaf to be turned from dragging on the top surface of the base, the latter has 70 arcuate ribs 30, on the bottom of which the leaf rides in the turning movement.

From the foregoing description taken in connection with the accompanying drawing, the advantages of the construction and 75 of the method of operation will be readily apparent to those skilled in the art to which the invention relates, and while we have described the principle of operation of the invention, together with the apparatus 80 which we now consider to be the best embodiment thereof, we desire to have it understood that the apparatus shown is merely illustrative and that such changes 85 may be made when desired as are within the scope of the claim.

What we claim as new and desire to secure by Letters Patent is:—

The combination of a supporting structure for a book, a leaf turning element 90 mounted thereon, and means mounted on the structure to operate the element including a member vertically mounted and slotted at its upper end, said element having a base formed of a ring to detachably fit around 95 the member, a cross key in the ring to engage in the slot of the member, vertical bars anchored at their lower ends in the ring, and leaf-engaging arms on the said bars.

In testimony whereof we affix our signatures in presence of two witnesses.

WILLIAM H. TRAYER.
FRANK CAMPBELL.
